UNITED STATES PATENT OFFICE.

PERCY TODD, OF GADSDEN, ALABAMA.

CUFF-HOLDER.

SPECIFICATION forming part of Letters Patent No. 783,331, dated February 21, 1905.

Application filed May 17, 1904. Serial No. 208,452.

To all whom it may concern:

Be it known that I, PERCY TODD, a subject of the King of England, residing at Gadsden, in the county of Etowah, State of Alabama, have invented certain new and useful Improvements in Cuff-Holders; and I do hereby declare the following to be a full, clear, and exact description of the invention, such as will enable others skilled in the art to which it appertains to make and use the same.

This invention relates to cuff-holders, and has for its object to provide a holder by means of which a cuff may be attached to the sleeve of a shirt, a further object being to provide a holder which will be adjustable to different lengths.

In the drawings forming a portion of this specification, and in which like numerals of reference indicate similar parts in the several views, Figure 1 is a side elevation of the present holder. Fig. 2 is a longitudinal section. Fig. 3 is a view of the blank from which a portion of the holder is formed. Fig. 4 is a detail perspective view of the sleeve. Fig. 5 is a side elevation of a modification. Fig. 6 is a longitudinal section of Fig. 5. Fig. 7 is a transverse section of Fig. 5. Fig. 8 is a detail perspective view of the sleeve used in the modified form. Fig. 9 is a detail view illustrating the spring and tongue.

Referring now to the drawings, the present holder comprises a rod 5, having a pivoted tongue 6 at one of its ends for engagement with the buttonhole of a cuff and having a sleeve 7 at its opposite end. The sleeve is formed from a metallic blank 8, which is rectangular in shape and which has ears 9 extending outwardly from its side edges in opposite directions at one of its ends, these ears being provided with perforations 10. In forming the sleeve the ears 9 are bent at right angles to the main portion of the blank in the same direction to bring their perforations 10 into alignment with each other, and beyond the ears the blank is bent at right angles to itself, as shown at 11, and then downwardly to form spaced portions 12 and 13, the portion 12 terminating just short of the ears 9.

A member 14 is provided, having serrations 15 on one of its edges and a laterally-extend-

ing finger 16 projecting from the serrated edge at one of the ends of the member, the finger 16 being bent into the form of an eye 17 and encircling the rod 5. The member 14 is engaged with the sleeve 7 and lies in the space 55 between the portions 12 and 13 and with its serrations 15 turned in the direction of the ears 9.

The rod 5 is engaged with the alining perforations 10 and has its ends headed over to 60 prevent withdrawal of the rod from the perforation, though free pivotal movement of the rod in the perforations 10 and the eye 17 is permitted. It will be readily understood that the edges of the ears 9 may be engaged 65 with the serrations 15 and that when thus engaged sliding movement of the rod 5 and member 14 longitudinally of each other is prevented, and in order to hold the ears 9 with their edges normally in engagement with the 70 serrations a bowed strap-spring 18 is secured at its center to the inner face of the portion 11 of the sleeve and bears with its ends against the edge of the member 14. When it is desired to disengage the edges of the ears from 75 the serrations 15, it is but necessary to press upon the portion 11 of the sleeve, which moves this portion of the sleeve toward the member 14 against the action of the spring 18, and the two portions of the holder are thus free to 80 slide longitudinally of each other and lengthen or shorten the holder, as desired.

Pivottally connected with the end of the member 14 opposite to that from which the finger 16 extends is a spring-clip 19 for engagement with the shirt-sleeve.

In Figs. 5, 6, 7, and 8 there is shown a modified form of the invention in which the member 14 is provided with a longitudinal slot 20 and with serrations 21 at one side of 90 the slot. A sleeve 22 similar to the sleeve 7 is slidably engaged with the member 14 and has parallel ears 23 and 24, which extend into the slot 20, these ears being provided with alining perforations 25, with which is engaged the inner end of the rod 5, this rod being provided with enlargements 26 and 27 outwardly of the ears 23 and 24, which prevent movement of the rod longitudinally in the perforations 25, though permitting the 100

rod to revolve freely therewithin. As shown, the rod 5 is slidably engaged in a passage 14' at one end of the member 14.

Secured to the rod 5 between the ears 23 and 24 is a spring-tongue 28, which extends toward the inner end of the rod and has its free end disposed to engage the serrations 21, the tongue being thus arranged to prevent movement of the rod and the sleeve in one direction. To move the tongue out of engagement with the serrations 21, the tongue carries a laterally-extending finger 29, which projects outwardly of the sleeve 22 through an opening 30 therein and may be engaged by the finger-nail to move the tongue. The rod 5 is arranged at its outer end for connection to a cuff, and the member 14 has pivotally connected thereto at the end opposite to the passage 14' a spring-clip 31 similar to the clip 19 in the preferred form provided for the purpose of attaching the holder to a garment.

In practice modifications of the specific construction shown may be made, and any suitable materials and proportions may be used for the various parts without departing from the spirit of the invention.

What is claimed is—

1. A cuff-holder comprising a rod arranged at one end for engagement with a cuff, a sleeve having ears extending across a portion of its opening at opposite ends thereof, said ears having alining perforations therethrough in which the other end of the rod is revolvably

engaged, a member slidably engaged in the sleeve, a guide carried by the member and in 35 which the rod is slidably engaged, means for holding the member at different points of its movement through the sleeve, and means carried by the member for engagement with a garment. 40

2. A cuff-holder comprising a rod having means at one end for engagement with a cuff, a sleeve engaged with the other end of the rod, said sleeve having ears extending across a portion of its opening at opposite ends thereof, said ears having alining perforations therethrough with which the end of the rod is pivotally engaged, a member slidably engaged with the opening of the sleeve and having a serrated edge turned in the direction of the 50 ears, a laterally-extending eye carried by the member and slidably engaged with the rod, said sleeve lying normally with the edges of its ears engaged with the serrations of the member, means for holding the sleeve yieldably in its normal position, said sleeve being movable against the action of the holding means to disengage the edges of its ears from the serrations. 55

In testimony whereof I affix my signature in 60 presence of two witnesses.

PERCY TODD.
